UNITED STATES PATENT OFFICE.

HILDING MOLLER, OF YOUNGSTOWN, OHIO, ASSIGNOR TO F. W. PERRY, OF YOUNGSTOWN, OHIO.

BRACKET.

1,305,922.

Specification of Letters Patent. Patented June 3, 1919.

Application filed March 8, 1918. Serial No. 221,225.

To all whom it may concern:

Be it known that I, HILDING MOLLER, a citizen of the United States, residing at Youngstown, in the county of Mahoning and

5 State of Ohio, have invented new and useful Improvements in Brackets, of which the following is a specification.

This invention relates to scaffolding supporting brackets and the principal object of 10 the invention is to provide means for securing the bracket to the uprights of the scaffolding without permanently securing said bracket to said uprights, such as by the use of nails or clamps.

15 Another object of the invention is to provide means for connecting the bracket with an upright in the form of a ladder or to a window and to provide means for adjusting said bracket so that the platform supporting 20 part thereof will lie in a horizontal plane whether or not the ladder is in a vertical or an inclined position.

Another object of the invention is to provide a device of this character which is simple and durable in construction, reliable and efficient in operation and one which can be manufactured and placed upon the market at a minimum cost.

The invention also consists in certain 30 other features of construction and in the combination and arrangement of the several parts, to be hereinafter fully described, illustrated in the accompanying drawings and specifically pointed out in the appended 35 claims.

In describing my invention in detail, reference will be had to the accompanying drawings wherein like characters denote like or corresponding parts throughout the several views, and in which:

Figure 1 is a perspective view of the bracket supplied with the various devices for connecting the same with the different forms of uprights and with a window casing.

45 Fig. 2 is a side view showing the bracket connected with an inclined ladder.

Fig. 3 is a like view showing the bracket applied to a vertical ladder.

Fig. 4 is a like view showing the bracket 50 applied to a ladder inclining in the opposite direction from that shown in Fig. 2.

Fig. 5 is a part sectional view of the main member of the bracket.

Fig. 6 is a sectional view of a detail.

Fig. 7 shows different forms of hook members which will be used with the bracket.

Fig. 8 is a part sectional view showing the bracket connected with the side of a window casing.

Fig. 9 is a section on line 9—9 of Fig. 8.

Fig. 10 is a view similar to Fig. 8 but showing the bracket secured to a window casing in a brick house.

Fig. 11 is a sectional view on line 11—11 of Fig. 10.

Fig. 12 is a view showing the bracket connected with the bottom part or sill of the window.

Figs. 13 and 14 are views of modifications.

Figs. 15 and 16 show a modification.

As shown in these views the bracket consists of a platform supporting member 1 preferably made of angle iron and having its rear end bent at right angles as at 2. This bent end is slotted as at 3 and a slide 4 having a hook 5 and provided with a slot 6 is adjustably secured to said end by means of the rivet 7 and a thumb screw 8. The other end of said member has the end of its horizontal web turned up as at 9 to form a

stop for the parts forming the platform and the end of the vertical web is enlarged to receive a pivot 10 which engages a slotted link 11. A second link 12 also slotted is held in engagement with the first link by the thumb screws 13. The link 12 is connected

with the vertical web of the member 1 by means of the link 14 pivotally connected at each end to said link and member. The free end of the link 12 is bent to provide a flat part of rest 15 and this part is extended to

form a flat hook 16 and this hook projects forwardly in front of said link 12 but below the same. A curved hook 17 is detachably connected to said rest by means of a thumb screw 18. 19 indicates a hook member removably secured to the vertical web of the member 1 by means of the thumb screws 20 and this hook 19 extends in an opposite direction to that of the hook 17 and is adapted to

coöperate with said hook to hold the bracket to a ladder or other support. 21 indicates a

pair of links pivoted to the horizontal web of the member 1 and are adapted to engage like members secured to a companion bracket or said members may be secured to the companion bracket by strips secured at the ends to said links. When not in use said links are folded under the horizontal web of the member 1. The bracket is also provided with a sill engaging hook 22 removably secured to the rear end of the horizontal web of the member 1 by the set screws 23. This hook is provided with a square recess 24 for engaging the inner part of the window-sill. A hook 25 is adapted to be detachably secured to the flat part 15 of the link 12 as shown in Figs. 2 and 3.

When the bracket is to be used on a ladder or other upright all the hooks excepting those designated by the numerals 17 and 19 may be removed, though it is not necessary to so remove these hooks. The hook 19 engages one edge of the upright while the hook 17 engages the other edge so that the weight of the bracket tends to clamp the upright between the hooks and the more the weight applied to the bracket the greater will be the clamping action. By means of the adjustable links 11 and 12 the member 1 of the bracket may be placed in a horizontal position no matter what position the upright assumes. Fig. 2 shows the bracket supporting the platform 26 in a horizontal position on an inclined ladder. In Fig. 3 the bracket is applied to a vertical ladder while in Fig. 4 the ladder is inclined in an opposite direction to that shown in Fig. 2. It will be understood that the bracket may be applied to any form of upright such as a 2x4 beam though ladders are usually used in this connection. By substituting hooks of different sizes, such as shown in Fig. 7 the bracket may be used on any size upright.

Figs. 8 and 9 show the device connected with the side of a window and in this case the adjustable hook 5 carried by the end 2 of the bracket engages the inner part of the window casing while the square hook 16 engages with the outer part of the casing. The same clamping effect is secured in this case as before. By means of the adjustable feature of the hook 5 the device may be used on different sizes of window-casings. It will be understood that in this case the hooks 17 and 19 are removed.

In Figs. 10 and 11 the bracket is shown connected with the window casing 27 of a house formed of brick as shown at 28. This is similar to the form shown in Figs. 8 and 9 excepting that the hook 25 is connected with the flat hook 16, taking the place of the hook 17 and this hook 25 engages the part 27 of the window-casing. This is necessary on account of the fact that the flat hook

16 cannot make a firm grip on the brick surface.

Fig. 12 shows the bracket connected with the bottom or sill of the window-casing, the sill being indicated by the numeral 29. The sill is engaged by the hook 22 provided with the recess 24 into which the sill fits. In this case the flat part 15 of the link 12 rests on the outer face of the wall of the building below the window.

In the modification shown in Fig. 13 the hook 16' is bent up from the end of the link 12' and the rest 15 omitted. The hook 25' is connected to this hook 16' so that the device may be used on a window such as shown in Figs. 8 and 9 by removing the hook 25' or said bracket may be used as shown in Figs. 80 10 and 11 by attaching said hook 25'.

In the modification shown in Fig. 14 the end of the supporting member 1' is bent into hook shape as shown at 2' while the end of the link 12' is also bent into hook shape as shown at 12'' so that these hooks are formed integral with the bracket. In this form the bracket is only adapted for use with the ladders or other uprights of the scaffold.

In the modification shown in Figs. 15 and 16 the bracket is made to be used with a circular upright A and in this form a chain 1'' is connected with the upper member 1'' of the bracket and the chain is provided with a spring 1''' to which is secured a hook, the chain being adapted to be wrapped around the upright to hold the bracket thereon. I prefer to place a strip of rubber or the like 1'' within the hooked part of the bracket to prevent slipping of the bracket on the upright. In this form of the device the lower member 2'' is provided with a bent part 2''' which rests against the upright.

It is thought from the foregoing description that the advantages and novel features of my invention will be readily apparent.

I desire it to be understood that I may make such changes in the construction and in the combination and arrangement of the several parts, provided that such changes fall within the scope of the appended claims.

What I claim is:—

1. A bracket comprising a supporting member having a hook at its inner end, an inclined member composed of a pair of slotted links adjustably connected together, one link being pivotally connected to the outer end of the supporting member, a hook at the end of the other link, said hooks being oppositely arranged, a link pivotally connecting the hooked ends together, and a pair of connecting links pivoted to the supporting member and adapted to be swung under the same.

2. A bracket comprising a supporting member having its inner end bent at right

angles, a hooked bar adjustably secured to said bent end, a removable hook having a square recess therein removably secured to said adjustable member adjacent the bent 5 end, a pair of links adjustably connected together and pivotally connected with the outer end of said supporting member, a link pivotally connecting the inner ends of said

supporting member and inner link together, the inner end of said link being bent to provide a rest and then extended forwardly and bent to provide a flat hook and a removable hook carried by said rest. 10

In testimony whereof I affix my signature.

HILDING MOLLER.
